UNITED STATES PATENT OFFICE.

ERNEST A. NEWMAN, OF WOBURN, MASSACHUSETTS.

RADIATOR.

1,072,637.

Specification of Letters Patent.

Patented Sept. 9, 1913.

Application filed January 13, 1913. Serial No. 741,690.

To all whom it may concern:

Be it known that I, ERNEST A. NEWMAN, a citizen of the United States, and a resident of Woburn, in the county of Middlesex and State of Massachusetts, have invented an Improvement in Radiators, of which the following description, in connection with the accompanying drawings, is a specification, like characters on the drawings representing like parts.

This invention relates to radiators and particularly to steam radiators, the object thereof being to provide means for varying or reducing at will the effective radiating surface thereof, thus controlling the temperature of the room wherein the radiator is located and also reducing the consumption of steam in moderate weather, with resulting economy of fuel.

In order that the principle of the invention may be readily understood, I have disclosed a single embodiment thereof in the accompanying drawings, wherein—

Figure 1 is a view partially in plan and partially in transverse longitudinal section of a steam radiator embodying my invention; Fig. 2 is a view of said radiator partially in side elevation and partially in longitudinal vertical section; Fig. 3 is a vertical transverse section taken through one of the radiator sections; and Fig. 4 is a longitudinal transverse section upon the line 4—4 of Fig. 2.

The proper regulation of the temperature of a room wherein a steam radiator is located is a matter of great difficulty, particularly during moderate weather. The fundamental requirement of a steam radiator is the use of steam, which has approximately a temperature of 212° F. If steam be admitted to such a radiator, it will by radiation heat the air of the room wherein it is located, to a degree too high for comfort in moderate weather. This necessitates frequent cutting off of the steam with the consequent lowering of the temperature of the room below the desired point and the re-admission of steam to the radiator, this practice being repeatedly followed with consequent marked variations in the temperature of the room.

The underlying purpose of my invention is the provision of means for varying or changing the effective radiating surface of the radiator, whereby, when the radiating surface is lessened, the heat radiated is cor-

respondingly lessened, and the amount of steam that will be condensed within the radiator is also correspondingly reduced.

In the course of my experiments to overcome the objection to which I have referred, I have discovered that if the air contacting or closely adjacent to the superficial portions of the radiator be there confined in heated condition and prevented from circulation about the room, those portions of the radiator surface with which such heated air is in contact cease to radiate heat. Thus the normal radiating surface is reduced by the area of those portions of the surface with which the confined hot air is in contact.

The purpose of my invention can be carried out in various ways and with various types of radiators, both of steam and of other types. I have, however, shown my invention as applied to a steam radiator composed of upright sections and have so constructed said sections that their outer walls constitute an inclosing chamber to which cold air may be admitted at the bottom and from which the exit of the air may be prevented. In this manner, the confined air is heated as described, and when the temperature thereof approximates the temperature of the contacting radiating surface, such surface ceases to act as a radiating surface and the radiation continues only from the remaining area of the radiator surface.

Referring more particularly to the figures of the drawing, the end sections of the radiator are represented at 1 and 2 and the intervening sections at 3, they being provided with suitable inlet and outlet passages. These sections may be of any suitable form structure and arrangement desired by the manufacturer. I have herein represented them as connected at their lower ends by nipples 4 and have shown the end sections as supported upon feet 5. At suitable points, as, for instance, near the upper ends of the sections, I may provide tie rods 6 or other suitable means to hold the sections in place. Each radiator section may have any suitable number of upright passages. In Fig. 3, I have represented one of the sections as provided with upright communicating passages 7, 8, 9 and 10, through which the steam circulates and between which are passages 11, 12 and 13 for the circulation of air about the steam passages

and which at the bottom between the sections are in open communication with the air of the room, as indicated at 13', thus permitting the free entrance of air between the sections.

5 By reference to Fig. 1, it will be noted that the outer walls of adjoining sections contact as indicated at 14, 15, thus preventing the lateral escape of the air from between the sections and compelling it to pass 10 upward and to escape at the top of the sections.

15 At some suitable point between the top and bottom of the radiator, as, for example, within the chamber 16 thereof. I position 20 means to prevent the escape of the heated air from the top of the radiator, thus confining it wholly between the sections thereof. For this purpose, I have represented a damper 17 having preferably a number of openings 18 corresponding with the number of 25 sections and positioned flatwise upon a plate 17' secured upon the top of the sections and having openings 18'. When these openings 30 are brought into register with the openings 18' and the spaces between the sections, then the air admitted at the bottom of the radiator is permitted freely to pass out at the top thereof and the normal radiating 35 surface is maintained. If, however, the damper is shifted so as to bring the openings thereof out of register with the spaces between the sections, then the air is confined, and when it has been brought to substantially the temperature of the radiator walls, 40 the air then serves as a blanketing or insulating means preventing further radiation of heat from the entire surface of each section, excepting the outer surface thereof, which is directly exposed to the air of the room.

The damper may be held in position and guided in its movement in any suitable manner, as by the provision of a slot 19 and bolt 45 20, and it may be operated in any suitable manner by means of a properly located handle 21 here shown as between the first and second radiating sections and concealed from observation. It is, however, to be understood that the damper may be operated in 50 any suitable manner. In order to prevent the escape of the air from the ends of the radiator, the two end sections 1, 2 have closed upright walls 22, 23. Thus when the 55 damper 17 is closed the air is wholly confined between the sections, as it cannot escape through the open bottom, because it is lighter than the air of the room. If desired, however, I may provide a damper adjacent 60 and controlling the admission openings 13', thus absolutely confining the heated air. It will be observed that I have provided means, herein embodied in the cross portion of the sections above the damper and constituting 65 top radiating walls, to direct air issuing

through the damper into contact with the portions of the sections located above the damper. I am thereby enabled additionally to heat the air discharged through the damper. Obviously, said air directing means 70 may be embodied in any suitable form.

The confined heated air acts, as it were, as an insulation applied to the inside radiating surface. The condensation of steam against such inside radiating surface is largely decreased when the damper is closed and therefore a less amount of steam is used. Material saving of fuel is thus effected.

Obviously, when the damper is partially opened, there is a slight or restricted circulation, and therefore degrees of temperature 80 may be obtained which are intermediate the maximum temperature occurring when the damper is fully opened and the minimum temperature occurring when the damper is 85 fully closed.

The damper 17 may be positioned at any suitable part of the radiator, as, for example, upon the top of the sections but underneath a correspondingly apertured secondary top or casing instead of as shown, in which case the air passages 11, 12, 13 may be continued uninterrupted to the top of the sections. The openings 18' at the bottom 95 between the sections for the admission of air may be made as large as desired by suitably tapering or otherwise shaping the said portions of the said sections.

I am aware that it has been heretofore proposed to provide a steam radiator with 100 sections contacting at their outer portions to compel the air to enter at the lower portion of the sections and permitting its escape only at the upper portion thereof, but in such case a constant circulation of air has 105 existed, and there has been no confinement of heated air to effect the purpose of my invention.

From the foregoing description, it will be clear that when the damper is closed, the radiating surface is limited to the outer surfaces of the passages 7, 10, and as the outer surfaces of said passages 7, 10 are of relatively small extent compared with the entire surface of said sections, namely, the entire surfaces of the passages 7, 8, 9, 10, it follows that far less heat is radiated, less steam is required to maintain the lessened radiating surface at the proper temperature because of the lessened steam condensation 115 120 and the temperature of the room is thus readily controlled.

The radiator herein disclosed is of simple yet effective construction and being of few parts is not liable to get out of order.

Having thus described one illustrative embodiment of my invention, I desire it to be understood that although specific terms are employed, they are used in a generic and descriptive sense and not for purposes of lim- 130

itation, the scope of the invention being set forth in the following claims.

Claims.

1. A steam radiator composed of a series 5 of communicating sections having outer, exposed side walls and top radiating walls between which latter the heated air may be discharged, the adjoining side walls of said sections being in continuous contact and the 10 end sections having closed end walls, said sections having inner radiating walls and means for admitting air thereto at the lower portion thereof, and a damper adjacent the top of the radiator but below the top radiating walls thereof, and adapted when closed wholly to prevent the egress of air from 15 said radiator.

2. A steam radiator composed of a series 20 of communicating sections having outer, exposed side walls in continuous contact, and inner radiating walls, the end sections of said series having closed end walls, means for admitting air to the lower portion of the radiator, a damper below but adjacent the top 25 of said sections and adapted, when closed, wholly to prevent the egress of air from said radiator, and means above said damper to direct air issuing therethrough into contact with the portions of said sections there- 30 above.

3. A steam radiator composed of a series 35 of communicating sections having outer, exposed side walls in continuous contact, and inner radiating walls, the end sections of said series having closed end walls, means for admitting air to the lower portion of the radiator, a damper below but adjacent the top of said sections and adapted, when closed, wholly to prevent the egress of air 40 from said radiator and means extending

transversely of the radiator above said damper to direct air issuing through the latter into contact with the portions of said sections above the damper.

4. A steam radiator composed of a plurality 45 of sections each having a plurality of spaced, upright steam passages providing upright air passages therebetween, the walls of the outer steam passages of said sections being in continuous contact and constituting 50 closed side radiator walls, and the end sections of the radiator having closed end walls, the radiator being provided with an air ingress opening at its lower portion and the sections having transverse air-deflecting, 55 connecting portions at their top between which the air is discharged, and a damper adjacent the top of the radiator but below said connecting portions, and adapted, when closed, wholly to prevent the egress of air 60 from the radiator.

5. A steam radiator composed of a series 65 of communicating sections having outer, exposed side walls and top radiating walls between which latter the heated air may be discharged, the adjoining side walls of said sections being in continuous contact and the end sections having closed end walls, means for admitting air to the lower portion of the radiator and a damper adjacent the top 70 of the radiator but below the top radiating walls, and adapted, when closed, wholly to prevent the egress of air from the radiator.

In testimony whereof, I have signed my 75 name to this specification, in the presence of two subscribing witnesses.
